United States Patent Office

Des. 224,153
Patented July 4, 1972

224,153

INSERT ROLL HOLD DOWN

James M. Lapeyre, 13 Richmond Place,
New Orleans, La. 70115

Filed Oct. 21, 1970, Ser. No. 25,572

Term of patent 14 years

Int. Cl. D15—99

U.S. Cl. D55—1

FIG. 1

FIG. 2

FIG. 3

FIG. 4

FIG. 5

FIG. 1 is a perspective view, looking from above and toward the front and left-hand end of the insert roll hold down;

FIG. 2 is a top view of the insert roll hold down;

FIG. 3 is a bottom plan view of the insert roll hold down;

FIG. 4 is a side elevational view of the insert roll hold down; and

FIG. 5 is an end elevational view looking from the right of FIG. 1.

I claim:

The ornamental design for an insert roll hold down, as shown.
